ATTORNEYS

UNITED STATES PATENT OFFICE.

JOHN SCHADE, OF STAMFORD, CONNECTICUT.

KNOB ATTACHMENT.

SPECIFICATION forming part of Letters Patent No. 350,397, dated October 5, 1886.

Application filed January 9, 1886. Serial No. 181,124. (No model.)

To all whom it may concern:

Be it known that I, JOHN SCHADE, a citizen of the United States, residing at Stamford, in the county of Fairfield and State of Connecticut, have invented certain new and useful Improvements in Knob Attachments; and I do declare the following to be a full, clear, and exact description of the invention, such as will enable others skilled in the art to 5 to which it appertains to make and use the same, reference being had to the accompanying drawings, and to letters or figures of reference marked thereon, which form a part of this specification.

15 Figure 1 of the drawings is a representation of the devices embodying my invention, and is a side view of a door-knob and spindle, a portion of the former being in section. Fig. 2 is a cross section taken on the broken line $x-x$, Fig. 1. Fig. 3 is a side view of the eccentric-bolt. Fig. 4 is a cross-section of said bolt on the broken line $y-y$, Fig. 3.

20 My invention has relation to devices for attaching knobs to their spindles; and it consists in the construction and novel combination of parts, as hereinafter set forth, and pointed out in the claims.

25 Referring by letter to the accompanying drawings, A designates the door-knob, B the knob-shank, and C the spindle, which spindle is rectangular in cross section. The seat D in the knob-shank is also rectangular in cross-section, so that the spindle will fit it snugly. At one side of the spindle-seat D, I provide a 30 cam seat or hole, E, in which I fit an eccentric-bolt or cam-bolt, F, having a niche in its upper end to receive the point of a screw-driver, so that said cam-bolt F may be turned to lock the spindle C in place in the seat D, or turned to unlock and release said spindle. 35 By this construction I dispense with washers and the like, to adapt the spindle to doors of

different thicknesses, for the reason that the cam-bolt will lock the spindle in its seat at any point of its length.

45 The upper and lower ends of the cam-bolt are cylindrical in cross-section, having journals which may be readily turned in their seats.

The metal on or at the edge of the hole or 50 seat E is prepared to prevent the cam bolt or pin F from falling out when not attached to the spindle by spinning or turning over the edge of the metal around the pin.

I attach importance to the employment of 55 the cam-bolt and to the fact that the spindle is of the ordinary construction, not being notched nor recessed.

I am aware that knob-shanks have heretofore been provided with threaded apertures, 60 knob-spindles notched and recessed, and tapering screws employed to fasten the knobs to the spindles, and therefore do not claim such devices broadly.

Having described this invention, what I 65 claim, and desire to secure by Letters Patent, is—

1. The combination, in a door-knob having its shank provided with a spindle-seat having a cam-seat at one side thereof, of the spindle and the cam-bolt F, substantially as specified.

2. The combination, with a door-knob having a spindle-seat formed with a cam-seat at the outside thereof, of the spindle and the cam-bolt F, secured in its seat by turning the metal of the shank upon the cam-bolt, substantially as specified.

75 In testimony whereof I affix my signature in presence of two witnesses.

JOHN SCHADE.
